HEADLESS TAMBOURINE

Henry J. Coito, 1325 Sycamore Ave.,
Modesto, Calif. 95350

Filed Nov. 14, 1966, Ser. No. 4,632

Term of patent 14 years

(Cl. D56—1)

FIG. 1

FIG. 2

FIG. 1 is a perspective view of the headless tambourine.
FIG. 2 is a cross section of one side of the frame of the tambourine; the view being taken substantially centrally through one set of jingles.

I claim:

The ornamental design for a headless tambourine, as shown and described.
